UNITED STATES PATENT OFFICE

112,360

DESIGN FOR A COMBINED MANUAL AND AUTOMATIC TUNING PANEL FOR AUTOMOBILE RADIO SETS

George W. Bill, Cincinnati, Ohio, assignor to The Crosley Radio Corporation, Cincinnati, Ohio, a corporation of Ohio

Application December 6, 1937, Serial No. 73,394

Term of patent 14 years

To all whom it may concern:

Be it known that I, George W. Bill, a citizen of the United States, residing in Cincinnati, in the county of Hamilton and State of Ohio, have invented a new, original, and ornamental Design for a Combined Manual and Automatic Tuning Panel for Automobile Radio Sets, of which the following is a specification, reference being had to the accompanying drawing, forming a part thereof.

In the drawing:

Figure 1 is a front elevation of a combined manual and automatic tuning panel for automobile radio sets, showing my new design.

Figure 2 is a side elevation of the panel.

I claim:

The ornamental design for a combined manual and automatic tuning panel for automobile radio sets, substantially as shown.

GEORGE W. BILL.
